(57) **CLAIM**

The ornamental design for a thermometer, as shown and described in the following Figures.

DESCRIPTION

FIG. 1 is a front perspective view of a thermometer of the present invention;

FIG. 2 is a back perspective view of the thermometer of the present invention;

FIG. 3 is a top view of the thermometer of the present invention;

FIG. 4 is a right side view of the thermometer of the present invention;

FIG. 5 is a front view of the thermometer of the present invention;

FIG. 6 is a back view of the thermometer of the present invention;

FIG. 7 is a left side view of the thermometer of the present invention; and,

FIG. 8 is a bottom view of the thermometer of the present invention.

The broken lines shown in the Figures are for illustration purposes only and form no part of the claimed design.
